UNITED STATES PATENT OFFICE.

OTIS A. MYGATT, OF NEW YORK, N. Y.

DESIGN FOR A REFLECTOR FOR ARTIFICIAL LIGHTS.

SPECIFICATION forming part of Design No. 35,755, dated February 18, 1902.

Application filed June 3, 1901. Serial No. 63,045. Term of patent 7 years.

To all whom it may concern:

Be it known that I, OTIS A. MYGATT, residing at New York, in the county of New York and State of New York, have invented and 5 produced a certain new and useful Design for a Reflector for Artificial Lights, of which the following is a specification, reference being had therein to the accompanying drawing.

The design relates to the form or configuration and the surface ornamentation of a transparent reflector for artificial lights.

The figure is a side elevation of the reflector embodying the design.

The reflector is composed of transparent 15 glass, and the form is that of the frustum of a cone A, surmounted by a ring B, of substan-

tially ogee form, as shown. The outer surface of the reflector is practically covered by spirally-arranged projecting ribs extending from near the top of the frustum to near the 20 lower edge thereof and terminating at the lower edge in small beads D.

What I claim, and desire to secure by Letters Patent, is—

The design for a transparent reflector for 25 artificial lights, as shown and described.

In testimony whereof I affix my signature in presence of two witnesses.

OTIS A. MYGATT.
